United States Patent [19]

Stowers et al.

[11] Patent Number: Des. 299,715

[45] Date of Patent: ** Feb. 7, 1989

[54] HIGH DENSITY RECEIVER MODULE

[75] Inventors: Jeffery P. Stowers, Mt. Sidney; Henri T. Burgers, Grottoes, both of Va.

[73] Assignee: Virginia Panel Corporation, Waynesboro, Va.

[**] Term: 14 Years

[21] Appl. No.: 804,584

[22] Filed: Dec. 4, 1985

[52] U.S. Cl. D13/24

[58] Field of Search D13/24-31; 439/660, 680, 157

[57] CLAIM

The ornamental design for a high density receiver module, as shown and described.

DESCRIPTION

FIG. 1 is a perspective view of a high density receiver module showing our new design.

FIG. 2 is an end elevational view thereof.

FIG. 3 is a side elevational view thereof.

FIG. 4 is an opposite side elevational view thereof.

FIG. 5 is a bottom plan view thereof.

FIG. 2

FIG. 3

FIG. 4

FIG. 5
